UNITED STATES PATENT OFFICE.

CHARLES W. MEEHAN, OF PITTSBURGH, PENNSYLVANIA.

LAMP.

Application filed August 29, 1925. Serial No. 53,436.

The present invention relates to lamps of the kind used for decorative as well as utilitarian purposes, such as those used in hotels, clubs, lodge rooms, and the like, where 5 lamps of considerable size are permissible and desirable.

The internal constructional features of the lamp in hand will be fully explained herein as the description proceeds, the object of 10 which is to provide a lamp of comparatively simple constructional details which will provide great rigidity and strength, and permit the use of a cement and metal lath base material, which in turn forms a suitable 15 surface on which blocks of tile of various attractive designs and shapes, may be properly mounted to form the exterior surface of the lamp stem and base.

The aforesaid interior construction of the 20 lamp is of an ingenious character and design, means being provided (and by using a comparatively small number of parts), for carrying the cement and metal lath shell on angle-iron uprights or supports; and a 25 removable conduit is also provided which runs through the center of the lamp base and stem, for carrying the necessary electric wires, or gas required for lighting purposes.

In the drawings forming part of the present 30 specification, I have shown a complete example, and a modification of the subject of the present invention, constructed according to the best mode so far devised for the purpose in hand.

35 In the drawings, Figure 1 is a vertical side elevation, partly in section of the invention.

Figure 2 is an enlarged vertical and central section of the lamp base, taken on line 40 2-2 of Figure 3.

Figure 3 is a horizontal section of the lamp base on line 3-3 of Figure 2.

Figure 4 is an enlarged vertical section of the upper portion of the lamp stem, taken 45 on line 4-4 of Figure 5.

Figure 5 is a horizontal section through the stem of the lamp on line 5-5 of Figure 4.

Figure 6 is a horizontal section of a lamp 50 stem and base, showing a modified form of same.

Figure 7 is a plan view of the metal cap-plate used with my invention.

Figure 8 is a front side elevation of Figure 55 7.

Figure 9 is a transverse sectional view of

a metal base-plate, taken on line 9-9 of Figure 3.

In the drawings the numeral 1 indicates the base of the lamp 2, same being composed of a wooden block 3, through which is preferably a central perforation 4; a metal base plate 5, having a number of cut-out portions 6, 7 forming tongues which project upwardly as shown in Figures 2 and 3. Castors 10, 10 are mounted in the bottom of the wooden block 3 in the usual fashion as shown, for moving the lamp around the room readily.

The stem 11 of the lamp 2 is composed 70 of preferably four angle-iron uprights 8, 9, etc. and placed to form a tapered stem of considerable height as shown in Figure 1 of the drawings.

The uprights 8, 9 are riveted or bolted at 75 points 12, 12, to the upstanding ends or metal tongues, 6, 7, of the aforesaid metal plate 5. At their upper ends the angle-iron uprights are fitted within a bent metal cap-plate 13, which has a central perforation 14, 80 and two depending flanges 15, 15 as shown in Figure 4 clearly. Two perforations 33, 33, are also made in the cap-plate 13 to permit lag-screws to pass therethrough for a purpose explained hereinafter. The angle-iron uprights 8, 9, are attached at points 16, 16 to the flanges 15, 15 of the cap-plate 13, by bolts or rivets as desired.

Upon the cap-plate 13 is mounted a wooden block 17, having a central perforation 18 90 formed complementary to that of the cap-plate 13, both of which provide a passage for the conduit 19 which passes through the vertical center of the lamp stem 11, to a point 20 at its base, where said conduit 95 makes preferably an abrupt turn as shown in Figures 2 and 3, to the exterior of the lamp base 1, at the point 21.

At its upper end the conduit 19 connects with the short upper support 22 of the lamp 100 as shown. It is evident that the conduit 19, may be used either for electric wires 23, 23, or if gas is used simply as a conduit for same. It is also seen that the conduit 19 can be disjointed at point 20, and withdrawn 105 vertically and upwardly, through the perforations 14 and 18 of the cap-plate 13 and block 17 respectively; while the horizontal portion of the conduit 19 can be withdrawn at point 21 from the base of the lamp. This 110 removable feature of the conduit is a very desirable one for repairing the lamp, as is at

once understood. The short upper support 22 of the lamp, is provided with a flanged bottom 24, usually for ornamental purposes, and said bottom flange can then be attached 5 to the upper wooden block 17 by means of lag-screws 25, 25 as seen in the Figure 4 of the drawings.

The lamp is provided with the usual lamp shade 26, within which are the usual electric 10 lamp bulbs, or gas burners (not shown), according to the system of lighting used.

The lamp stem 11, and base 1, is further composed of an inner layer, 27 of cement mounted on metal lath, and said cement 15 layer forms a proper base material on which is mounted a number of tiles 28, 29, preferably glazed, and of various colors, and designs as shown in Figure 1; said tiles being adapted to cover all the exterior faces of 20 the lamp stem and base. It will be noted that the corner tiles at points 30, 31, 32 are suitably curved or rounded for ornamental 25 purposes, and that a variety of colors, shapes, and designs may be used for these tiles, all of which lends beauty and attractiveness to the lamp as a whole, and making the lamp a

very desirable, useful, and ornamental feature of club rooms, hotel, and the like.

It is noted that while the Figures 1 to 5 inclusive, show a lamp stem and base of 30 rectangular outline, that said lamp can by slight modification be made of a circular cross-section such as illustrated by the Figure 6 of the drawings, in which case the exterior tiles and cement base must be arranged to suit the roundness of the curved outline, as is at once understood.

I claim:—

In a lamp, a number of upstanding angle-irons forming a support for the stem of the 40 lamp, a metal base-plate having a series of up-turned tongues formed thereon, each one of which connects with one of the angle-irons, for holding the latter in rigid relation to each other, a bent-metal cap-plate rigidly 45 connecting the upper ends of the angle-irons to each other, an enclosing shell of cement and tile, covering the lamp stem and base, and a removable conduit passing through the 50 stem and base of the lamp.

In testimony whereof I affix my signature.
CHARLES W. MEEHAN.
